UNITED STATES PATENT OFFICE.

JAKOB HOJNOWSKI, OF NEKOOSA, WISCONSIN.

CONCRETE RAILROAD TIE.

Application filed May 5, 1922. Serial No. 558,610.

To all whom it may concern:

Be it known that I, JAKOB HOJNOWSKI, a citizen of Poland, residing at Nekoosa, in the county of Wood and State of Wisconsin, have invented certain new and useful Improvements in Concrete Railroad Ties, of which the following is a specification.

This invention relates to the ties or sleepers used to support the rails of railroad tracks, the invention having for an object to provide a novel form of railroad tie of cheap construction.

More specifically speaking the invention has for an object to provide a simple form of reinforced concrete tie or sleeper and a novel arrangement of fastening means for securing the rails thereto.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view of a portion of a railroad track having the invention embodied therein.

Fig. 2 is a fragmentary longitudinal sectional view, taken just beside one of the rails and showing one of the ties in transverse section.

Fig. 3 is a detail fragmentary perspective view of the reinforcing element of the tie.

Fig. 4 is a perspective view showing the tie partially completed.

Fig. 5 is a perspective view of the completed tie.

Fig. 6 is another perspective view of the completed tie, showing the bottom face thereof.

Figs. 7, 8, 9 and 10 are detail perspective views of the different fastening bolts employed.

In the drawing the reference numeral 10 indicates a pair of track rails of ordinary construction which are supported by and secured to my improved ties. These ties are indicated generally at 11 and comprise concrete bodies reinforced by metal elements of sheet form. In Fig. 3 I have shown in detail a suitable form of metal reinforcing elements which consists of a sheet of wire mesh or expanded metal 12 bent to form a central horizontal element 12' which extends 55 along the bottom part of the tie, being then bent to present a pair of angular or in-

verted L-shaped channels 13 whose inner adjacent sides 14 are formed by the marginal portions of the sheet, these marginal portions extending vertically of the finished tie midway between opposite sides thereof, the angular channeled elements, which are arranged back to back forming together a completed structure of T-form in cross section which is the form of the completed tie, 65 the laterally projecting top flanges of the tie being indicated at 11'.

In constructing the tie the reinforcing element 12 is bent to the proper shape and filled with concrete, suitable rods 18, which 70 are afterwards withdrawn, being passed through the concrete, the holes in the concrete left when the rods are withdrawn being adapted to receive the fastening bolts, further reference to these details being presently made. The tie being formed is placed in a suitable mold, which is packed with concrete in which the reinforcing element is embedded a suitable distance. As indicated in Figs. 5 and 6 I may employ additional reinforcing strips 20 extending longitudinally of the tie within the channeled elements 13. As indicated at 20 in Fig. 6 the bottom face of the tie may be transversely corrugated.

Referring now to the means for securing the rail to the tie, the rods 18 are suitably positioned and constructed to leave four transverse rows of holes in the tie, arranged in two pairs of rows which register with 90 the edges of the base flanges of the rails, there being three holes in each row. The side holes, indicated at 22, extend vertically through the side flanges 11' at the top of the tie, while the centre holes, 23, are of 95 parti-circular, curvature extending from the top of the tie outwardly through the side thereof under the flanges 11', the respective centre holes of adjacent rows being preferably curved in opposite directions to open 100 at their lower ends at opposite sides of the tie. Through the side holes 22 are passed bolts 24 having T-heads 25 on their lower ends which engage under the flanges 11', and having nuts 26 threaded on their upper 105 ends engaging over the base-flanges of the rails. Through the centre holes 23 are passed correspondingly curved bolts which may be of the type shown in Fig. 8 comprising curved shanks 27 having heads 28 110 on their lower ends adapted to engage the sides of the tie, and nuts 29 threaded on

their upper ends adapted to bear on the base-flange of the rail. Or these bolts may be of the type shown in Fig. 9, comprising curved shanks 30 having laterally projected 5 spike-heads 31 on their upper ends adapted to engage over the base-flanges of the rails, and having nuts 32 threaded on their lower ends and bearing on the sides of the tie.

In certain cases the tie may comprise a 10 concrete body 33 of rectangular cross section with straight sides and provided with a reinforcement 34, or it may comprise a body 35 having inwardly sloping sides 36. In connection with this latter type of tie I 15 may use the bolt shown in Fig. 10, comprising a straight shank 37 having a laterally projected spike head 38 on its upper end, so positioned, or arranged at such an angle, as to lie flat on the base-flange of the 20 rail when the bolt is inclined downwardly and laterally to project at its lower end, on which is threaded a nut 39, through the inclined side of the tie.

It will be understood that various other 25 changes and modifications might be made in the construction of my improved tie and rail fastening means without departing from the spirit and scope of the invention as defined in the appended claims.

30 Having thus described my invention what I claim as new and desire to protect by Letters Patent of the United States is as follows:

1. A railroad tie comprising a concrete 35 body of T-shape in cross section, and a reinforcing element comprising a metallic sheet formed into a pair of L-shaped elements arranged back to back.

2. A railroad tie comprising a concrete 40 body of T-shape in cross section, and a re-

inforcing element comprising a metallic sheet formed into a pair of L-shaped elements arranged back to back, the backs of said L-shaped elements being formed by the side portions of the said metallic sheet. 45

3. A railroad tie comprising a concrete body of T-shape in cross section, and a reinforcing element therefor likewise of T-shape in cross section, the horizontal top flanges of said tie having vertical openings 50 therethrough.

4. A railroad tie comprising a concrete body of T-shape in cross section, and a reinforcing element therefor likewise of T-shape in cross section, said tie having openings extending downwardly therethrough from points approximately midway between 55 its sides, said openings leading outwardly through the sides of the tie.

5. A railroad tie comprising a concrete 60 body of T-shape in cross section, and a reinforcing element therefor likewise of T-shape in cross section, said tie having openings extending downwardly therethrough from points approximately midway between 65 its sides, said openings leading outwardly through the sides of the tie, and being curved throughout their length.

6. In combination, a track rail, a concrete tie of T-shape in cross section on which said 70 rail rests, fastening bolts engaging the rail on opposite sides thereof and extending downwardly through the top flanges thereof, and other fastening bolts engaging the rail between the first mentioned bolts and 75 passing through the body of the tie and outwardly through the sides thereof.

In testimony whereof I have affixed my signature.

JAKOB HOJNOWSKI.
